(57) **CLAIM**

The ornamental design for a folding pouch, as shown and described.

DESCRIPTION

FIG. 1 is a view of the pouch prior to folding;

FIG. 2 is a top perspective view of the folding pouch showing my new design; and,

FIG. 3 is a bottom perspective view thereof.

The broken lines shown in FIG. 1 indicate fold lines and are part of the claimed design.

1 Claim, 3 Drawing Sheets

FIG.1

FIG. 2
